(57) CLAIM

The original design for a bento box shaped purse, as shown and described.

DESCRIPTION

FIG. 1 is a top perspective view of the bento box shaped purse showing my new design in an open configuration; FIG. 2 is a top perspective view showing a closed configuration;

FIG. 3 is a front view;

FIG. 4 is a left side view;

FIG. 5 is a right side view;

FIG. 6 is a back view;

FIG. 7 is a top view; and,

FIG. 8 is a bottom view.

The curved broken line showing of the handle is for illustrative purposes only and forms no part of the claimed design.

The smaller broken lines that represent stitching on the strap are for illustrative purposes only and form no part of the claimed design.

1 Claim, 4 Drawing Sheets
